GEORGE P. KNAPP, OF BRIDGEPORT, CONNECTICUT, ASSIGNEE TO HARVEY HUBBELL,
INCORPORATED, OF BRIDGEPORT, CONNECTICUT, A CORPORATION OF CONNECTICUT.

ELECTRIC SOCKET AND SHADE-HOLDER.

1,138,297.

Specification of Letters Patent.

Patented May 4, 1915.

Application filed August 3, 1914. Serial No. 854,743.

To all whom it may concern:

Be it known that I, George P. KNAPP, a citizen of the United States, residing at Bridgeport, county of Fairfield, State of Connecticut, have invented an Improvement in Electric Sockets and Shade-Holders, of which the following is a specification.

This invention relates to electrical fixtures and has for its object to provide a socket of either the pull, key or keyless type which shall be adapted to lock a shade holder or husk between the body of the socket and the cap, thereby permitting the socket to be locked to the conductor pipe by means of an exposed set screw and doing away with the necessity of using a shouldered connection between the socket cap and the pipe.

Heretofore so far as I am aware it has been the practice to lock the shade holder or husk between the socket cap and a shoulder upon a fitting that was interposed between the socket and the pipe, the fitting being provided with a female thread to receive a male thread upon the end of the pipe. This has made it impracticable to use a set screw to secure the socket cap to the pipe, as the cap was covered by the shade holder, and has led to the use of cements and similar means for setting the threads together which made it impossible to detach the socket from the pipe without the use of considerable force resulting frequently in the breakage of parts. In my present invention, the shade holder or husk is locked between the body and cap of the socket, the neck of the cap engaging the pipe directly, that is without the interposition of a shouldered fitting and being detachably locked to the pipe by means of a set screw.

In the accompanying drawing forming a part of this specification, Figure 1 is a view, partly in elevation and partly in section, on the line 1—1 in Fig. 2, looking in the direction of the arrows, of an electric socket and shade holder, illustrating my novel invention; Fig. 2 a plan view with the socket cap removed, the connecting screws being in section on the line 2—2 in Fig. 1, looking in the direction of the arrows; Fig. 3 a section on the line 3—3 in Fig. 2, looking in the direction of the arrows; Fig. 4 a plan view of the upper member of the body detached, and Fig. 5 is an inverted plan view of the cap detached.

10 and 11 denote respectively the upper

and lower members of the body which are ordinarily made of porcelain and are secured together by screws 12, 13 the cap which is ordinarily made of metal and is secured to the upper member of the body by screws 14, and 15 is a shade holder or husk, it being understood that the essential difference between a shade holder and a husk is that the latter is ordinarily made ornamental and is not intended to carry a shade. 60 Body member 10 is provided in its upper side with recesses 16 and with a circular shoulder 17 upon which an inwardly extending flange 18 upon the shade holder or husk rests. The shade holder or husk (for 70 convenience I will use the term "shade holder" only) is additionally provided with inwardly extending lugs 19 which are adapted to lie in the recesses 16. The cap is provided with a flange 20 which rests upon the 75 flange of the shade holder and with bosses or blocks 21 which are adapted to pass into the recesses in the upper body member and rest upon the lugs extending from the shade holder. The shade holder is locked between 80 the upper body member and the cap by the screws 14 which pass through the upper body member and the lugs on the shade holder and engage the cap. The cap is provided with the usual female thread, but in 85 use instead of engaging a fitting, as heretofore, engages the pipe (not shown) directly, the fitting being dispensed with. The cap is locked in place on the pipe by set screw 22 which is always accessible, this not being 90 the case when the shade holder is secured in place by locking it between the cap (the shade holder covering the cap) and a shouldered fixture on the pipe, which I dispense with.

95 The operation of assembling is as follows: The shade holder is placed over the upper body member with the flange resting on the shoulder and the lugs engaging the recesses, then the cap is placed over said 100 body member and the shade holder with the bosses in the recesses and resting on the lugs and then the shade holder is locked to place between the upper body member and the cap by turning screws 14 to place, said 105 screws being socketed in the body member and passing through the lugs on the shade holder and engaging the cap. The upper body member, carrying the shade holder and cap, is then placed in position over the 110

lower body member and locked thereto by turning screws 12 to place.

Having thus described my invention I claim:

- 5 1. The combination with a socket body having recesses, of a shade holder having lugs engaging said recesses, and a cap having bosses engaging said recesses and gripping the lugs upon the shade holder.
- 10 2. The combination with a socket body having a shoulder and recesses, of a shade holder having a flange adapted to rest on the shoulder and lugs adapted to engage the recesses, and a cap having bosses adapted to 15 pass into the recesses and grip the lugs upon the shade holder.
- 20 3. The combination with a socket body having a shoulder and recesses, of a shade holder having a flange adapted to rest on the shoulder and lugs adapted to engage the recesses, and a cap having a flange adapted to engage the flange on the shade holder and bosses adapted to pass into the recesses in the body and grip upon the shade holder.
- 25 4. The combination with a socket body comprising upper and lower members, said upper member having recesses, of a shade holder having lugs engaging said recesses, a cap having bosses engaging the recesses and

gripping the lugs upon the shade holder 30 and means for attaching the body members together after the shade holder has been locked between the upper member and the cap.

5. The combination with a socket body 35 comprising upper and lower members, and a cap, of a shade holder gripped between the upper member and the cap, means for securing the upper member and cap together with the shade holder in place, and means 40 for securing the body members together after the shade holder is locked in place.

6. The combination with a socket body comprising upper and lower members, said upper member having a shoulder and recesses and a cap having bosses engaging said recesses, of a shade holder having a flange adapted to engage the shoulder and lugs adapted to engage the recesses and be gripped by the bosses, and means for securing the upper member and cap together and for securing the members together. 45

In testimony whereof I affix my signature in presence of two witnesses.

GEORGE P. KNAPP.
